UNITED STATES PATENT OFFICE.

ALVAH W. CLEMENT, OF HOPEDALE, MASSACHUSETTS, ASSIGNOR TO THE DRAPER COMPANY, OF SAME PLACE AND PORTLAND, MAINE.

LOOM.

SPECIFICATION forming part of Letters Patent No. 641,763, dated January 23, 1900.

Application filed August 17, 1899. Serial No. 727,472. (No model.)

To all whom it may concern:

Be it known that I, ALVAH W. CLEMENT, of Hopedale, county of Worcester, State of Massachusetts, have invented an Improvement in Looms, of which the following description, in connection with the accompanying drawings, is a specification, like letters and figures on the drawings representing like parts.

This invention relates more particularly to looms provided with automatic filling-supplying mechanism controlled by or through a feeler which at intervals feels the filling in the shuttle and which when the filling has been exhausted to a predetermined extent causes the supplying mechanism to operate to effect the introduction of a fresh supply of filling, a loom of this type forming the subject-matter of United States Patent No. 626,187, dated May 30, 1899.

As the fresh filling is transferred the partially-spent filling-supply is ejected from the shuttle, carrying with it the end of filling leading from the edge of the cloth; and my present invention has for its object the production of means to part or sever this filling end, so that not only will the length of thread pulled away by the ejected filling-carrier be as short as possible, but the parting means will carry the length of filling between it and the edge of the cloth into position to be parted or severed by a thread-cutting temple closely adjacent the edge of the cloth.

I have herein shown one practical embodiment of my invention as applied to a loom of the character shown in Patent No. 626,187, referred to, and to operate in conjunction with a thread-cutting temple, such as shown in United States Patent No. 585,465, dated June 29, 1897; but my invention is not restricted in its application to such construction of loom nor to the thread-cutting temple herein shown.

Various novel features of my invention will be hereinafter described in the specification and particularly pointed out in the claims.

Figure 1 is a front elevation of a sufficient portion of a loom to be understood, taken at the side provided with filling-supplying mechanism and having one embodiment of my invention applied thereto. Fig. 2 is a right-hand side elevation of the apparatus shown

in Fig. 1 with the lay-back and the filling-parting means in normal position. Fig. 3 is an enlarged top or plan view of a portion of the loom, showing the parting means in operative position and just before the end of filling between said means and the edge of the cloth is brought into position to be engaged by the thread-cutting temple, also shown. Fig. 4 is a perspective view, enlarged, of the breast-beam at the left-hand side of the loom, showing the feeler and a portion of the connecting devices between it and the thread-parting means. Fig. 5 is an enlarged inner side elevation of the parting means in normal position. Fig. 6 is a similar view showing the parting means in position to grasp and to sever the filling when the transerrer is operated to effect a change of filling. Fig. 6^a is a detached view of one of the jaws of the filling-holder shown in Figs. 5 and 6. Fig. 6^b is a perspective view of the coöperating jaw thereof. Fig. 7 is an inner side elevation of the filling-parter *per se*; and Fig. 8 is a detached view of the segmental lifter which operates to open the parting and holding members, said arm being shown in dotted lines, Fig. 1.

In carrying out my invention I have so constructed and arranged the filling-parting means that they will only operate when the shuttle is properly boxed, said means acting as a shuttle-feeler to detect the improper boxing of the shuttle.

Referring now to Figs. 1 and 2, the loom-frame A, breast-beam A⁴⁰, the lay A³, having the bottom of one of its shuttle-boxes cut away below the self-threading shuttle S to permit the passage therethrough of an ejected filling-carrier, the filling-supplying mechanism, comprising connected rotatable plates suitably shaped to hold the filling-carriers b, the stud f, transerrer f', mounted thereon and having the depending end f³ and a finger 21, and the shaft d', adapted to be rotated by or through the feeler upon exhaustion of the filling to a predetermined extent, are and may be all substantially as shown in United States Patent No. 628,228, dated July 4, 1899, to which reference may be had. As in said patent, the end f³ of the transerrer has mounted upon it a headed rocker-stud m, controlled

by a spring s , said stud having an arm m^2 , provided with a lateral lug m^4 , said arm having an attached notched dog m^x to be engaged by a bunter C^2 on the lay when a change 5 of filling is to be effected.

The loom-frame is provided with a bracket A^{10} , on which is pivoted at 10 a yoke Y , one of its upturned arms y' directly engaging the lug m^4 , a lateral stud or projection y^2 on its 10 other arm, and preferably provided with an antifriction-roll 7 , being normally engaged by a detent-finger d^x , fast on the rock-shaft d' and normally maintained in the position 15 shown by a strong spring S^x , attached at its ends to said finger and to the loom-frame, respectively. In said Patent No. 628,228 the other arm of the yoke Y is upturned and bent rearwardly to form a shuttle-feeler, and in my present invention said arm y is upturned 20 and bent rearwardly; but it is bifurcated to form two branches p^x and h^x , (see Fig. 3,) the former supporting the parting devices and the latter having mounted upon it the holding 25 means for the filling-end. The rearwardly-extended end of the branch p^x is notched at p' , Fig. 7, and a steel blade p^2 is fixed to the inner face of the branch, with its sharpened edge above the notch, while a movable blade p^3 is mounted to rock on a pin or stud 25, extended 30 from one to the other branch, said blade being held from free movement by a suitable friction-washer 26, Fig. 3. At its front end the movable blade has a cam-slot p^4 , adapted to be entered by the reduced end 35 p^6 of a laterally-extended lug p^5 , attached to an actuating-arm p^7 , herein shown as mounted on the end of the stud 25, projecting beyond the branch h^x and frictionally held by a washer 27, the lateral lug p^5 traveling in a 40 slot 28 in the branch h^x . (See Fig. 6.)

Referring to Fig. 5, wherein the actuating-arm p^7 is shown in normal position and against a stop 29, the lug p^5 will have moved downward past the fulcrum 25 of the arm p^7 far 45 enough to engage the bottom of the slot p^4 and rock or tip the blade p^3 , thereby wiping its cutting edge over the edge of the fixed blade p^2 , the parting device being thus maintained normally closed.

50 The branch h^x is cut away at its extremity to leave an overhanging projection h' , on which is mounted a weighted jaw h^2 , fulcrumed at 30 and having a slot 31 near its front end to receive a guide-stud 32, the enlarged base h^3 of the jaw being shown in Fig. 6^b as longitudinally concaved to form a seat for a facing h^4 of rubber or other suitable yielding material, the weight of the jaw h^2 being sufficient to turn it into the position 55 shown in Fig. 6 when free to move, the holding device, comprising the jaws h^2 and h^5 , then being open. The coöperating jaw h^5 is shown detached in Fig. 6^a, it having an upturned hooked front end h^6 to receive a pivot h^7 , by 60 65 by which it is fulcrumed on the branch h^x , the hooked end being notched on its upper edge, as at h^8 , to receive the pin or stud 25

when the jaws are closed, the front upright edge of the jaw being straight from 3 to 4 and then curved to form a notch or recess h^9 . 70

When the actuating-arm p^7 is in normal position, Fig. 5, the lateral lug p^5 rests against the front edge of the jaw h^5 , below the upper corner 4 thereof, positively maintaining the latter in engagement with the concaved portion h^3 of the "gravity-jaw" h^2 , as it may be termed, the front end of the latter being lifted relative to its fulcrum 30. When, however, the actuating-arm p^7 is lifted into dotted-line position, Fig. 5, as will be described, the lug p^5 operates to first open the blades of the parting device and then as the lug travels up along the edge 34 of the jaw h^5 to open said jaw as the lug arrives at the upper corner 4, the notch h^9 affording a clearance for the lug 80 at such time. As the jaw h^5 is thus rocked into open position the gravity-jaw h^2 moves into the relative position shown in Fig. 6, and the parting and holding devices are ready to operate upon the filling-thread when the latter has been exhausted to a predetermined extent. 85

Referring now to Fig. 4, the filling-feeler a^x is shown as forming part of an arm a^9 , pivotally mounted at a^6 on the feeler-carrier a^4 , as 90 in United States Patent No. 626,187, the feeler entering the shuttle through an opening therein and through a slot in the front wall of the shuttle-box, and, as described in said patent, the feeler contacts with the filling 95 when the lay beats up, so that when the filling is exhausted to a predetermined extent a stud a^{13} will contact with the shuttle-body before the feeler engages the filling. The arm a^9 will then be swung inward, viewing Fig. 4, and a dagger a^{15} on said arm will engage a 100 spring-controlled blade a^{23} and rock its supporting-stud a^{22} as the lay completes its forward movement, such rocking of the stud moving a link c^2 in the direction of the arrow 105 50, Fig. 4, to actuate a setting-cam c , which in turn acts on a dog d^6 to rock the arm d^4 and bring a latch connected therewith and not shown herein into position to be acted upon by the usual weft-hammer, the arm d^4 being fulcrumed at d^3 on a finger d^2 , fast on the rock-shaft d' , all as in said Patent No. 626,187. When the weft-hammer engages the latch, the arm d^4 is operated to rock the shaft d' through its attached finger d^2 in the 110 direction of the arrow 55, Fig. 2, the detent-finger d^x will be raised, permitting the spring s to turn the dog m^x into position to be engaged by the bunter C^2 , and at the same time the lug m^4 will act upon the arm y' to swing 115 the yoke Y upon its fulcrum 10, and if the shuttle is properly boxed the bifurcated end of the arm y will be moved into the position shown in Fig. 6, directly above and adjacent the raceway of the lay, as the latter completes 120 its forward beat.

The stand 9, Fig. 4, is provided with an extension, upon which is fulcrumed at c^{30} a lever c^{31} , forked or notched at its upper end to

embrace a pin c^{32} on a collar c^{33} , adjustably secured by a set-screw c^{34} on the link c^2 , the lower end of said lever having pivotally connected therewith one end of a rod c^{35} , the other end of said rod being pivotally connected with a short depending ear c^{36} , (see Figs. 1 and 8,) fast on a shaft c^{37} , mounted to rock in a part A^{15} of the bracket A^{10} , secured to the loom-frame, said shaft being at right angles to the fulcrum 10 of the yoke Y. At its rear end said shaft c^{37} has secured thereto by a set-screw 80, Figs. 5 and 6, the hub of a lifter c^{38} , shown as a segmental arm extended beneath the widened end p^{12} of the actuating-arm p^7 , the lifter moving the arm p^7 to effect the opening of the thread parting and holding devices.

When the link c^2 is moved longitudinally, as has been described, the lever c^{31} is rocked to move the rod c^{35} oppositely to the arrow 50 and the shaft c^{37} is rocked to raise the lifter c^{38} into dotted-line position, Fig. 5, to thereby raise the outer end of the actuating-arm p^7 into dotted-line position, placing the holding and parting devices in condition to receive the filling-thread, as has been described. This separation of the blades of the parting device and the jaws of the holding device takes place before the shaft d' has been rocked, so that when the latter is operated the yoke swings back and assumes the position shown in Figs. 3 and 6 as the lay completes its forward stroke, it being supposed that the shuttle is properly boxed, the filling-thread t entering between the jaws $h^2 h^5$ and the blades $p^2 p^3$.

The transerrer f' has an elongated hub f^{12} , Fig. 1, which passes through the stand A^8 , and an arm f^{13} is secured to the projecting end of the hub, said arm having pivotally connected therewith at f^{14} a depending leg f^{15} , reduced at its lower end at f^{16} to leave a shoulder f^{17} , the end f^{16} passing between the branches p^X of the yoke-arm y and between the laterally-extended lug p^5 and a friction-roll p^{18} , mounted on a stud p^{14} , extended from one to the other branch, as herein shown. With the parts in the position shown in Fig. 6, when the transerrer f' descends to effect a transfer of filling the depression of the leg f^{15} brings the shoulder f^{17} into engagement with the lug p^5 and depresses it until the arm p^7 is stopped by the stop 29, the roll p^{18} engaging and guiding the leg until the arm p^7 reaches its normal position relative to the yoke, and then the space between the lug p^5 and the roll p^{18} will have increased sufficiently to permit the shoulder f^{17} to pass by the lug as the transerrer completes its transferring movement. As the lug p^5 is thus depressed it acts to close the jaw h^5 against its fellow h^2 before the part p^6 of said lug has engaged the bottom of the slot p^4 of the movable cutting-blade p^3 , so that the filling is engaged and held by the holding device before it is severed by the blades of the parting device. This prevents the filling from twisting out of the range of the holding device, as it

would be apt to do were it severed before being held, as described. As soon, however, as the filling-thread is firmly held by the holding device the parting device operates to part or sever the thread near the shuttle, as will be evident from an inspection of Fig. 3, so that when the partially-exhausted filling-carrier is ejected from the shuttle by the entrance of 75 the fresh supply of filling the length t' of filling carried away by such ejected filling-carrier will be as short as possible, it being usual to provide a box or other convenient receptacle for the ejected filling-carriers. The filling end is now severed and its loose end is held between the jaws of the holding device, and as the filling-transferrer resumes its normal position, rocking the arm f^{13} to lift the leg f^{15} , the rock-shaft d' will be released in 85 the usual manner to permit the spring S^X to depress the detent-finger d^X , thereby returning the yoke Y to its normal position, (shown in Fig. 5,) it being remembered that the holding device still retains its grasp upon the filling end. As the yoke swings into normal position the filling end is drawn forward and into the path of the cutting device of a thread-cutting temple, (shown only in Figs. 2 and 3,) the temple herein illustrated forming the subject-matter of United States Patent No. 585,465, hereinbefore referred to, it being only necessary to herein state that the movable member c^{20} of the temple-cutter co-operates with a fixed member or blade a^{20} , the movable member being hooked (see Fig. 2) and operating as in the patent referred to, the filling end being brought against the fixed blade by the movement of the yoke hereinbefore referred to, after which the movable cutter c^{20} on the temple is operated at the next forward beat of the lay, the hooked end of such movable cutter drawing the filling against the blade a^{20} and severing it. I have in Figs. 2 and 3 indicated the temple as a whole by T. After the thread has been thus cut adjacent the selvage of the cloth a short piece remains retained by the holding device, and it will be so retained until the actuating-arm p^7 is again moved from full to dotted line position, viewing Fig. 5, to separate the holding-jaws $h^2 h^5$, whereupon the thread will be released. The flexible or non-metallic facing of one of the jaws of the holding device enables the filling end to be held, yet without running the risk of severing it by pinching when the jaws are closed.

The filling-thread is not rigidly held by the jaws of the holding device, but is permitted to draw through as the said device returns to normal inoperative position, since the distance to the edge of the cloth at such time is greater than when the holding device is in position to hold the thread—viz., directly over the lay.

The branches $h^X p^X$ are considerably separated, as shown, so as to permit the thread to draw through the jaws after being parted, but not to be entirely released.

Should the shuttle be improperly boxed when the yoke Y is moved toward the lay, the end of the branch p^x will engage the shuttle and, operating precisely as does the shuttle-feeler y^x in United States Patent No. 628,228, will prevent the movement of the dog m^x into position to be engaged by the bunter C², and the transfer of filling will be prevented. The movement of the yoke into operative position is governed by a suitable set-screw 90, mounted in an ear A¹⁶ of the bracket A¹⁰, the set-screw being held in adjusted position by a suitable lock-nut 95, said set-screw acting as a stop for the yoke when it reaches its operative position, as shown in Fig. 6.

My invention is not restricted to the precise construction and arrangement herein shown and described, as various modifications may be made or a rearrangement of parts effected without departing from the spirit and scope of my invention.

It will be manifest from the foregoing description that my invention is equally well adapted for use with other forms of feeler-looms and with any other suitable form of thread-cutting temple.

Having described my invention, what I claim as new, and desire to secure by Letters Patent, is—

30 1. In a loom provided with filling-supplying mechanism, a temple having a filling-cutter and located at the filling-changing side of the loom, a shuttle adapted to carry a supply of filling, and means to hold and to part the thread of the filling-carrier to be ejected upon a change of filling and operated at such time by said filling-supplying mechanism, the return movement of the thread-holding means bringing the filling end held thereby into position to be severed by the temple-cutter.

45 2. In a loom provided with filling-supplying mechanism, a temple having a filling-cutter and located at the filling-changing side of the loom, a shuttle adapted to carry a supply of filling, a swinging support, means mounted thereon to hold and to part the thread of the filling-carrier to be ejected upon a change of filling, said mechanism at such time effecting the movement of said support into operative position, a filling-feeler operative upon exhaustion of the filling to a predetermined extent to effect the actuation of the filling-supplying means, and controlling devices governed by the filling-feeler, to cause the 55 thread to be held, and thereafter parted between the holding means and the filling-carrier.

60 3. In a loom provided with filling-supplying mechanism, a temple having a filling-cutter and located at the filling-changing side of the loom, a shuttle adapted to carry a supply of filling, means to hold, and means to part the thread of the filling-carrier to be ejected upon a change of filling, a common, movable support upon which said means are mounted side by side, said support being moved into operative position by or through the action of the

filling-supplying mechanism when changing filling, a filling-feeler to effect the operation of said mechanism upon exhaustion of the filling to a predetermined extent, devices governed by said feeler, to place the holding and the parting means in condition to operate prior to the change of filling, and independent devices actuated by the filling-supplying mechanism to cause the holding means to engage the thread and thereafter to actuate the parting means to sever it, the return of the support to normal position operating through the holding means to bring the filling end into position to be severed by the temple-cutter adjacent the edge of the cloth.

4. In a loom provided with filling-supplying mechanism, a thread-cutting temple, a swinging yoke governed by said mechanism, normally-closed thread-holding jaws and severing-blades mounted upon said yoke, means controlled by the filling-feeler to open said jaws and blades, a filling-feeler to effect the actuation of the filling-supplying mechanism when the filling is exhausted to a predetermined extent, such actuation permitting the yoke to move the jaws and blades into operative position relative to the thread of the filling-carrier to be ejected, and means governed by the operation of the filling-supplying mechanism to first close the jaws upon the thread and thereafter to close the blades to sever it, the return of the yoke to normal position acting through the holding-jaws to bring the filling end into position to be severed by the temple-cutter.

5. In a loom, filling-supplying mechanism including a transfferer, a shuttle-feeler operatively connected with said mechanism, thread-parting means and thread-holding means mounted on the shuttle-feeler, a filling-feeler to effect the operation of said mechanism upon exhaustion of the filling in the shuttle to a predetermined extent, a device controlled by the feeler to place said holding and parting means in operative condition, the shuttle-feeler moving said holding and parting means into position to hold and part the thread of the filling-carrier to be ejected when the shuttle is properly boxed, a device operatively connected with the transfferer to close said holding means upon the thread and to thereafter actuate the parting means as the change of filling is effected, and a thread-cutting temple located at the filling-changing side of the loom, the return of the shuttle-feeler to normal position operating through the holding means to bring the thread into position to be cut at the temple.

6. In a loom provided with filling-supplying mechanism, a filling-feeler to effect the operation thereof upon the exhaustion of the filling in the shuttle to a predetermined extent, a bifurcated swinging arm having mounted upon it fixed and movable thread-parting blades and thread-holding jaws, an actuating-arm connected with one of the holding-jaws and with the movable blade to actuate

them, a lifter in engagement with said actuating-arm when the parts are in normal position, connections between the filling-feeler and said lifter to operate the latter and thereby open the jaws and blades prior to a change of filling, and independent means operatively connected with the filling-supplying mechanism to successively close the jaws upon the thread and to close the blades to part it adjacent the filling-carrier to be ejected.

7. In a loom, filling-supplying mechanism including a transerrer, a swinging yoke operatively connected with said mechanism and normally held in inoperative position, thread-holding jaws and parting means mounted upon said yoke, actuating devices to open and close the jaws and operate the parting means, a filling-feeler to effect the operation of the filling-supplying mechanism upon exhaustion of the filling in the shuttle to a predetermined extent, means intermediate the filling-feeler and the device for operating the jaws and parting means to place said jaws and parting means in operative position when a change of filling is to be effected, and a depending leg operatively connected with the transerrer to close the jaws upon the thread and to thereafter actuate the parting means to part the thread as the change of filling is made.

8. In a loom, a bifurcated arm, fixed and movable parting-blades mounted thereon, a gravity-jaw and a coöperating positively-movable jaw to engage and hold the thread of a filling-carrier to be ejected, means to close the jaws and the blades and including an actuating-arm, filling-supplying mechanism, a filling-feeler to effect the operation of said mechanism upon exhaustion of the filling to a predetermined extent, a lifter controlled by the feeler to move said actuating-arm to open the blades and jaws, and independent means to close them operated by or through the action of the filling-supplying mechanism upon a change of filling.

9. In a loom, a bifurcated shuttle-feeler, fixed and movable parting-blades mounted thereupon, a pivotally-mounted holding-jaw, and a coöperating gravity-actuated jaw both mounted upon the shuttle-feeler adjacent the parting-blades, an actuating-arm fulcrumed on the shuttle-feeler and provided with a transversely-extended lug adapted to enter a slot in the movable blade and to engage and move one of the holding-jaws, means to en-

gage and move said arm in one direction to open the jaws and blades to receive a filling-thread between them, and independent means to engage and depress the laterally-extended lug to thereby close the holding-jaws, and thereafter close the blades to part the thread.

10. In a loom provided with filling-supplying mechanism, a shuttle-feeler operatively connected therewith and provided with thread holding and parting means, movable into position when said mechanism is operated to effect a change in filling, a thread-cutting temple, a filling-feeler to effect the operation of the filling-supplying mechanism upon exhaustion of the filling in the shuttle to a predetermined extent, means controlled by said feeler to place the holding and parting means in active condition before the movement of the shuttle-feeler takes place, and independent means controlled by the filling-supplying mechanism to engage a thread by the holding means and to thereafter part it as the filling-carrier is ejected, the return of the shuttle-feeler to normal position acting through the holding means to bring the end of filling into position to be severed by the temple-cutter.

11. In a loom provided with filling-supplying mechanism, a filling-feeler to effect the operation thereof upon the exhaustion of the filling in the shuttle to a predetermined extent, a shuttle-feeler operatively connected with said mechanism, flat holding-jaws and thread-parting means mounted upon the shuttle-feeler, devices including an actuating-arm to govern the action of said jaws and parting means, means controlled by the filling-feeler to open the jaws and place the parting means in condition to act upon the thread of the filling-carrier to be ejected, a device operated by the filling-supplying mechanism to close the jaws upon the thread and to thereafter operate the parting means to part the thread when a change of filling is effected, and a temple provided with a thread-cutter adapted to part the thread between the cloth and the holding-jaws as the latter return with the shuttle-feeler to normal position.

In testimony whereof I have signed my name to this specification in the presence of two subscribing witnesses.

ALVAH W. CLEMENT.
